UNITED STATES PATENT OFFICE.

MARTIN R. GRISWOLD, OF WATERTOWN, CONNECTICUT.

ARRANGEMENT OF ROLLERS FOR MAKING METAL TUBES.

Specification of Letters Patent No. 12,739, dated April 17, 1855.

To all whom it may concern:

Be it known that I, MARTIN R. GRISWOLD, of Watertown, in Litchfield county and State of Connecticut, have invented a new and useful Machine for Making Seamless Metal Tubes and for Working other Masses of Metal in a Cylindrical Form; and I do hereby declare that the following is a full, clear, and exact description of the construction and operation of the same, reference being had to the annexed drawings, making a part of this specification, in which—

Figure 1 is a perspective view of the machine. Figs. 2, 3, and 4, are different parts 15 of said machine.

Fig. 4 represents the contour of a tapering serrated roller, of which there are two in the machine B, B, having the points of the projections rounded off, the roller decreasing in diameter to conform to the decreasing diameter of the material while being wrought. Each roller is let into a case A, A, and their relative position shown in Fig. 2, one case being suspended over the other, with the representation of a tube T, between the rollers B, B. A perpendicular plane drawn through the axis of each roller, will cross at the point of contact with the tube T. By revolving the rollers in the same direction and with the same velocity, the tube T will be revolved on its own axis in an opposite direction, the tube being at an equal angle from each roller is drawn through between them, on a line nearly parallel to the axis of the rollers, and leaving a spiral indentation around the tube resembling the thread of a screw. The serrated working face of the rollers elongates and at the same time gives a cylindrical form to the material wrought. Like results may be obtained by having the working face of the rollers cut spirally like the thread of a screw, the axis of the tube and rollers being upon the same plane, but the first described methods are preferable, as any desired pitch, coarse or fine is easily obtained. The less the angle at which the rollers cross each other the more uniform their action on the whole surface of the materials wrought.

The cases A, A, containing the rollers B, B, are held firmly in their places in the frame, by pivots through their centers, secured to the frame, allowing the cases A, A, to be turned, thereby causing the axis of the rollers to cross at any desired angle. Rollers with plane polished faces, are arranged as

first described, for drawing and finishing the materials in the later part of the process.

The cases, A, A, and rollers B, B, are placed in a stout iron frame as seen in Fig. 1. Between them and secured to the frame is the guide plate (Fig. 3) having an opening in its center sufficient to admit the lower roller B, through to its upper surface. On the top of this guide plate are secured two slides C, C, by bolt and nut; said slides and bolts approach and recede from the middle of the guide plate by means of set screws, passing through puppet heads cast on the guide plate. On the ends of each slide C, C, and contiguous to each other is a loose guide roller D, D. Projecting in front and rear are two arms V, V, secured to each slide having their ends shaped like the letter V, for the purpose of guiding and keeping the material wrought in its proper place between the rollers B, B. The working roller B, above the guide plate approaches to, and recedes from the lower roller B by means of screws E, E, as seen in Fig. 2, acting on the movable boxes of the roller B, in the upper case, thereby allowing any variety of sizes to be wrought with one pair of rollers.

On the top of the frame Fig. 1 and behind it is seen a pulley G, on a shaft leading to the pulley H, through the standard P. Said standard is secured to the movable box for the bearing of the upper roller B, and moves up or down with it. The above said shaft is connected at the middle by the universal joint I. The pulley H, connects by a gear chain with the pulley on the end of the upper roller B. The pulley G, connects in a like manner with a like pulley on the bottom of the frame (not seen) and this with the shaft and universal joint, with the pulley K, said shaft passing through the support U, which is secured to the lower case A, and moves with it. The pulley on the end of the lower roller B, is geared to the pulley K. Now any motion communicated to either shaft on the top or bottom of the frame will be transmitted to the rollers B, B, by the gearing above described, the universal joints L, and I, admitting any desired change in the direction of the axis of the rollers B, B, whether in active operation or not; this change is effected by gearing connecting the cases A, A, holding the rollers B, B, to the perpendicular shaft M. The upper gear chain N passes through the frame and crosses. The bottom chain O passes to the

bottom case A, without crossing. By turning the shaft M, with a lever an opposite movement is given to the cases A, A, and of course to the direction of the axis of the 5 rollers B, B. After thus reversing them, the tube must come from the opposite side of the frame and end of the rollers, and a reversed spiral indentation like a left hand- 10 ed screw is made on the tube by the rollers, although they revolve the same way as before.

What I claim as of my invention, and desire to secure by Letters Patent, is The arrangement of the adjustable smooth or serrated rollers, whose axes cross each 15 other as herein set forth, with the guide plate, and slides, and guide rollers, for making seamless metal tubes as described.

MARTIN R. GRISWOLD
